(57) **CLAIM**

The ornamental design for a faucet set, as shown and described.

DESCRIPTION

FIG. 1 is a perspective view of a faucet set showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is the first operational embodiment thereof;

FIG. 9 is the second operational embodiment thereof;

FIG. 10 is the third operational embodiment thereof;

FIG. 11 is the fourth operational embodiment thereof;

FIG. 12 is the fifth operational embodiment thereof;

FIG. 13 is the sixth operational embodiment thereof; and,

FIG. 14 is the seventh operational embodiment thereof.

The broken lines shown in the faucet spout, the circular area on the faucet base, the water flow director, and the large base are included for the purpose of illustrating a portion of the faucet set that forms no part of the claimed design.
